UNITED STATES PATENT OFFICE.

FREEBORN F. RAYMOND, 2d, OF NEWTON, MASSACHUSETTS.

HEEL-ATTACHING MACHINE.

SPECIFICATION forming part of Letters Patent No. 394,298, dated December 11, 1888.

Application filed April 27, 1888. Serial No. 272,023. (No model.)

To all whom it may concern:

Be it known that I, FREEBORN F. RAYMOND, 2d, of Newton, in the county of Middlesex and State of Massachusetts, a citizen of the 5 United States, have invented a new and useful Improvement in Heel-Attaching Machines, of which the following is a full, clear, and exact description, reference being had to the accompanying drawings, forming a part 10 of this specification, in explaining its nature.

The invention relates especially to devices for attaching a French or ogee heel. French or ogee heels have generally been attached to the soles of a boot or shoe in two parts or 15 divisions by successive nailing operations, although they have also been secured by a single gang or group of nails driven from the tread end of the heel, which nails are caused to take an outwardly-inclined path as they 20 are driven by first forming outwardly - inclined awl-holes. By my invention the heel-blank is attached by nails driven simultaneously, some of which are driven from the tread end of the heel-blank and some from 25 the riser or first section of the blank. The heel-blanks for French heels are usually made in two parts—viz., the seat-section and the tread-section. The seat-section is usually considerably longer than the tread-section, and 30 the object of making the blanks in two parts is to save stock and to facilitate the attachment where they are secured in successive order. These sections are sometimes called “decks.”

To carry my invention into effect, I employ 35 a templet which has two levels or bearing-surfaces, one of which rests against the outer surface of the lower deck or section and the other of which against the surface of the upper deck or the tread end of the heel; and I also employ awls carried by the same plate or head, but preferably varying in length, the longer being adapted to form the holes in the lower deck and the shorter the holes in both 40 decks, but extending from the upper surface of the upper deck. I also use drivers carried by the same plate or head to be operated simultaneously, but which vary in length, the longer of which are adapted to drive the 45 attaching-nails into the lower deck, and preferably sufficiently below the level thereof as to leave the heads out of the path of the heel

trimmer or cutter. The shorter drivers are adapted to drive the nails through both decks either flush with the upper surface of the upper deck or to extend therefrom for blind-nailing the top lift. 55

In the drawings, Figure 1 is a view, part in section and part in side elevation, of the central and upper parts of a heel-nailing machine 60 having my improvement. Fig. 2 is a view, part in front elevation and part in cross vertical section, of the central and upper parts of a heel-nailing machine to further illustrate my invention. Fig. 3 is a plan view of the 65 templet and nail-carrier. Fig. 4 is a plan view of a section of a templet, to which reference is hereinafter made. Fig. 5 is a view in vertical section of a portion of a shoe and heel, representing in dotted outline the heel-blank 70 before it is trimmed. Fig. 6 is a view in plan inverted of an ogee heel and a section of the sole of the shoe to still further illustrate the operation of the invention.

A represents the last or work-support; a, the 75 slide-jack, upon which it is mounted; a', the bed of the machine upon which the jack is arranged to slide.

B is a table, which, preferably, is provided with a vertical movement upon a post, b, in 80 opposition to spring-pressure, and which has a slideway in which is secured the templet C, and which, preferably, is horizontally movable therein.

D is the nail-carrier. 85

E is the cross-head, which is reciprocated preferably substantially as described in Patent No. 316,894. It carries a revolving head, e, having radiating arms, one of which supports the gang or group of awls e', another the 90 gang or group of drivers e², and the third a top-lift holder and spanker, e³. The templet C comprises the imperforate section c and the section c', which is provided with the holes c⁵. The templet also has the section or part c³, 95 having the curved face c⁴ and holes c⁶, which are in continuation of the holes c⁵ of the plate. This section c³ has a pressing or bearing surface, c⁶, upon a lower or different level than the pressing or bearing surface c⁷ of the main 100 part of the templet, and it is adapted to bear against the upper surface of the lower heel-deck. While it may be made integral with the templet C, it is preferable to make it detacha-

ble, in order that sections of greater or less height for use with longer or shorter heels may be substituted, and in Fig. 1 of the drawings I have represented it as made a separate piece and secured to the templet by the screws c^8 .

It will be seen that the templet C has the line of holes c^2 , through which the nails which are driven through both decks of the heel are fed or delivered to it, and the line of holes c^5 , which delivers nails to the lower deck of the heel only. The awls e' may be of the same length; or, if desired, those which operate to prick the lower deck only may be made somewhat longer than those which prick both decks. The gang e^2 of drivers has the short drivers e^4 , which drive the nails through the holes c^2 of the templet into the upper deck of the heel-blank, and the long drivers e^5 , which drive the nails through the holes c^5 into the lower deck of the heel-blank, and which, preferably, are long enough to extend below the bearing-surface c^6 when in their lowest position to enter the lower deck of the heel-blank and drive the nails any desired distance below said surface, so as to leave sufficient stock to be removed in shaping the heel without striking the heads of the nails. Of course the trimmed heel-blank will have holes midway 30 its height before it is finished; but these holes are filled with suitable filling in the finishing of the heel-blank.

In use the boot or shoe is placed upon the last or work-support, the lower section or deck 35 placed upon the heel end of the outsole and so that its rear section extends under the surface c^6 of the templet, the upper deck is placed so that its edge bears against the curved front c^4 of the lower section, c^3 , of the templet, and 40 the table B and templet C are then moved downward, the heel-blank clamped upon the boot or shoe, and while thus held it is pricked by the reciprocation of the awls which form the holes f in the lower deck and also the holes f' in the upper and lower deck simultaneously. 45 The attaching-nails are then fed to the holes c^2 c^5 of the templet by the nail-carrier D, which has a like arrangement of holes for holding the nails. Longer nails, however, are fed to 50 the holes c^2 than to the holes c^5 , as it is necessary that they should extend through the upper and lower decks into the soles of the boot or shoe, while the other nails extend only from the lower deck. The drivers are then 55 brought into position and reciprocated, and the long and short nails are simultaneously

driven, the long nails through both decks into the soles of the boot or shoe and the shorter nails into the lower deck and soles of the boot or shoe, the heads of the shorter nails being 60 driven, preferably, below the surface of the deck, as represented in Fig. 1, by making the drivers extend below the surface c^6 of the templet. This brings the heads of these nails below or within the finished line of the heel. 65 (See Fig. 5.)

Having thus fully described my invention, I claim and desire to secure by Letters Patent of the United States—

1. In a heel-attaching machine, a templet 70 for driving nails at different levels, having the bearing or pressing surface c^6 , the bearing or pressing surface c^7 , and the holes c^2 c^5 , substantially as described.

2. The combination of the templet having 75 the holes c^2 and pressing-surface c^7 with the removable section c^3 , having the holes c^5 , substantially as described.

3. The combination of the templet C, having the holes c^2 c^5 , the section c^3 , having the 80 bearing-surface c^6 , and the front curved edge, c^4 , and holes c^5 , substantially as described.

4. The combination of the last or work-support, the templet having the bearing-surfaces c^6 c^7 , the holes c^5 c^2 , with the gang of awls to 85 enter the holes c^2 c^5 and a gang of drivers to enter said holes, and comprising the group of short drivers e^4 and the group of long drivers e^5 , substantially as described.

5. The combination of the last or work-support, 90 the templet having the two bearing-surfaces c^6 c^7 at different levels, and holes c^2 , extending to the one level, the holes c^5 , extending to the other level, and a gang of drivers in two groups, the shorter of which are adapted 95 to drive nails through the shorter holes and the longer of which are adapted to drive nails through the longer holes and to extend below the ends of said holes to drive nails below the level of the deck of the heel, substantially as 100 described.

6. The combination, in a heel-nailing machine, of a templet having holes c^5 with a gang of drivers of a length greater than the length of the holes, and suitable operating mechanism for reciprocating the drivers to bring their driving ends below the ends of said holes, as 105 and for the purposes described.
